(57) **CLAIM**

The ornamental design for a shaker, as shown and described.

DESCRIPTION

FIG. 1 is a front perspective view of the shaker;

FIG. 2 is a top plan view thereof;

FIG. 3 is a bottom plan view thereof;

FIG. 4 is a left-side elevation view thereof;

FIG. 5 is a right-side elevation view thereof;

FIG. 6 is a rear elevation view thereof; and,

FIG. 7 is a front elevation view thereof.

The broken lines in the drawings depict portions of the shaker that form no part of the claimed design.

1 Claim, 7 Drawing Sheets
